UNITED STATES PATENT OFFICE.

FRANK A. HALLECK, OF CHICAGO, ILLINOIS, ASSIGNOR TO SULLIVAN MACHINERY COMPANY, A CORPORATION OF MASSACHUSETTS.

VALVE MECHANISM.

Application filed April 5, 1922. Serial No. 549,898.

My invention relates to valve mechanisms, and more particularly to valve mechanisms for compressors or other pumping machinery.

5 An object of my invention is to provide an improved valve mechanism. Another object of my invention is to provide an improved valve mechanism for compressors or other pumping mechanisms in which smooth operation is insured. A further object of my invention is to provide an improved automatic valve mechanism for pumping devices in which breakage of valves or springs is reduced to a minimum and a very smooth 10 and silent operation is accomplished. Other objects and advantages of my invention will hereinafter more fully appear.

In the accompanying drawings I have shown for purposes of illustration one form 20 which my invention may assume in practice.

In these drawings,—

Fig. 1 is a central vertical section through a fragment of the compressor cylinder with an illustrative embodiment of my invention 25 employed in connection therewith.

Fig. 2 is a plan view of the buffer plate constituting a portion of my invention.

Fig. 3 is an edge view thereof and Fig. 4 is a central section on the line 4—4 of 30 Fig. 2.

Fig. 5 is a plan view of the spring.

Fig. 6 is a side elevation of the spring before insertion in the assembled mechanism.

I employ my invention with a cylinder 35 member 1 having a bore 2, said cylinder member being provided with a head 3 having a chamber 4 communicating with the bore 2 and constituting an extension of the counterbore of the cylinder. Within the 40 cylinder head is arranged a series of recesses 5, which recesses receive my improved valve mechanisms and of which recesses but one is shown. These recesses communicate with a discharge chamber 6 formed in the cylinder and with an inlet chamber 7 formed in the head. In the recesses 5 I locate my improved valve mechanisms, these comprising cooperating inlet and discharge portions, respectively designated 9 and 10, which portions are held in assembled relation by a 45 through bolt 11 and which are held in the cylinder head by the connection of the bolt 11 with a bar 12 which extends across the open ends of the recesses 5 in the head member 3.

Considering the inlet and discharge members 9 and 10 separately, the former will be first examined. This comprises a generally annular member 13 traversed by a series of 60 passages 14 which communicate with the inlet chamber 7 at one end and at the other with ports 15 which open through the lower side of the member 13. The member 13 is provided with an annular shoulder 16 which seats upon a surface 17 on the head 65 member 3 and serves to position the member 13 with respect thereto. The member 13 is also provided with a plurality of projecting bosses 18, of which but one is shown herein, these bosses serving as guides for the 70 valve and spring later described and also supporting an annular guard plate 19 which is secured to the member 13 by bolts 20 and nuts 21, of which but one is shown. A central recess 22 is provided in the member 13 75 to permit the latter to pass down over a nut which will later be described and which holds the element 10 in position. An annular valve member of relatively thin material 23 seats over the ports 15 and is held 80 normally closing the same by means of a spiral spring 24 of flattened material. This spring is best shown in Figs. 5 and 6 and will be noted to be ribbon-like and may be made up in practice by flattening a spiral 85 spring of round stock. Between the lower side of the spring 24 and the guard 19 is a buffer plate best shown in Figs. 2, 3 and 4, this plate being substantially annular and of substantially the same dimensions as the 90 valve member 23. This buffer plate, which is designated 25, will be noted to be provided a series of corrugations or flexures whose axes of flexion extend radially with respect to the member 25. As a result of this construction, a light and resilient buffer plate is provided and possible breakage of the spring 24 or the valve 23 is practically 95 eliminated by reason of the elasticity of the buffer plate and, further, a more silent operation is rendered possible.

The element 10, which is the discharge element, comprises a member 26 which is similar to the member 13 in a number of respects. This member is traversed by a 105 series of flow passages 27 which open into the space intermediate the members 9 and 10 and communicating with the cylinder counterbore 4, and terminate in ports 28 which are normally closed by an annular 110

valve 29. This valve 29, which is of thin stock, is held closed by a spring 30 similar to the spring 24, and a guard 31 secured by nut and bolt means 32 upon depending bosses 33 corresponds to the guard plate 19 of the element 9. A buffer plate 25 corresponding to the buffer plate 25 is disposed between the guard and spring. The member 26 is provided with a surface 34 which seats upon the annular shoulder 35 in the head member 3. A nut 36 is threaded upon the bolt 11 and holds the member 26 with its surface 34 in engagement with the shoulder 35, while a nut 37 holds the member 13 with its shoulder 16 in engagement with the surface 17 of the head 2.

The mode of operation of this device will be readily apparent. Upon the suction stroke of the piston, the valve 23 will be unseated, compressing the spring 24 and, by reason of the spiral form of the spring, the same may flatten down into a single plane and provide a very wide port opening. Owing to the presence of the buffer plate 25, severe hammering of the valve and spring are prevented. On the compression stroke, the valve 29 will open while the valve 23 will be closed by the spring. The spring 30 and the buffer plate 25 will operate as did the spring 24 and buffer plate 25 in the intake position of my valve mechanism.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A valve mechanism comprising a member provided with a port, a thin valve overlying said port, a guard having a normally immovable relation to said member, a resilient member constituting per se a yielding stop spaced from said port and supported by said guard, and a spring of smaller cross section than said resilient stop disposed between said valve member and said resilient member.

2. A valve mechanism comprising a member provided with a port, a thin valve overlying said port, a guard having an immovable relation to said member, a resilient member constituting per se a yielding stop spaced from said port and supported by said guard, and a spiral spring of greater resiliency than said resilient stop disposed between said valve member and said resilient member and directly engaging each of the same.

3. A valve mechanism comprising a member provided with a port, a thin valve overlying said port, a guard having an immovable relation to said member, a corrugated resilient member spaced from said port and supported by said guard, and a spiral spring disposed between said valve member and said corrugated resilient member.

4. A valve mechanism comprising a member provided with a port, a thin valve overlying said port, a guard having a normally immovable relation to said member, a resilient member constituting per se a yielding stop held in position by said guard opposite said port, said resilient member being formed with a permanent flexure therein, and a spiral spring of greater resiliency than said flexed member disposed between said valve and member, said spring engaging said valve member substantially adjacent its periphery.

5. A valve mechanism comprising a ported member, a guard spaced from and having an immovable relation to said member, a valve overlying said ported member, a resilient member flexed along intersecting lines and supported by said guard on the side thereof towards the valve, and a spring disposed between said valve and resilient member.

6. A valve mechanism comprising a ported member, a guard spaced from and having an immovable relation to said member, a valve overlying said ported member, a resilient member flexed along intersecting lines and supported by said guard on the side thereof towards the valve, and a spiral spring disposed between said valve and resilient member.

In testimony whereof I affix my signature.

FRANK A. HALLECK.

CERTIFICATE OF CORRECTION.

Patent No. 1,659,816

Granted February 21, 1928, to

FRANK A. HALLECK.

It is hereby certified that error appears in the printed specification of the above numbered patent requiring correction as follows: Page 1, line 92, after the word "provided" insert the word "with"; and that the said Letters Patent should be read with this correction therein that the same may conform to the record of the case in the Patent Office.

Signed and sealed this 20th day of March, A. D. 1928.

Seal.

**M. J. Moore,
Acting Commissioner of Patents.**
